DORF, GERMANY, A CORPORATION OF GERMANY.

CASEMATE-GUN.

1,183,050.

Specification of Letters Patent. Patented May 16, 1916.

Application filed June 22, 1915. Serial No. 35,687.

To all whom it may concern:

Be it known that we, KARL VÖLLER, a subject of the German Emperor, residing at 12 Scharnhorststrasse, Dusseldorf, Germany, and CARL WANINGER, a subject of the German Emperor, residing at 128 Uerdingerstrasse, Dusseldorf, Germany, have invented 5 certain new and useful Improvements in Casemate-Guns; and we do hereby declare the following to be a full, clear, and exact 10 description of the invention, such as will enable others skilled in the art to which it appertains to make and use the same.

With casemate guns hitherto known positioned behind a straight casemate wall it was possible to direct the gun within a horizontal angle of say 60°. If it was desired to gain a horizontal range of larger extension it was necessary to mount a second gun 15 behind a wall forming an angle with the first wall so that by the combined use of both guns a larger horizontal angle could be swept.

Our present invention has for its object to 20 enable one single gun to sweep a relatively large horizontal range, and obtains this object by an arrangement by means of which the gun can be brought quickly from one embrasure of the wall to another. For this 25 purpose the gun is mounted rotatably on a plate arranged behind the whole system and is further provided with a spherical member adapted to close the embrasure and to be shifted on the gun barrel.

An embodiment of our invention is shown 30 in the accompanying drawing by Figure 1 in a side elevation partly in section and by Fig. 2 in a plan view.

The gun barrel *a* is mounted in any known 35 manner on a standard *b* pivotally connected with a plate *c*. The plate *c* is provided at its rear end with a vertical pivot *d* project-

ing into a suitable socket arranged in the bottom plate. Thus the whole gun may be turned around the axis *d*. Connected with 45 the plate *c* is a further plate *e* serving as platform for the squad and rotated around the axis *d* together with the whole gun.

If it is desired to turn the gun so as to bring it from the embrasure *f* into the embrasure *g* it will be necessary to disconnect the spherical member *h* from the embrasure. This spherical closing member *h* is shiftable 50 on the gun barrel by means of ears *i* guided on rods *k* fastened on the cradle *l*. In consequence thereof the closing member can be withdrawn from the embrasure whereupon 55 the whole gun can be turned around the axis *d* and brought before the embrasure *g*. The closing member *h* is then shifted toward the 60 embrasure *g* so as to close the latter.

Having thus described our invention what we claim is:

1. In a casemate gun the combination of a 65 plate connected with the gun and rotatable around a vertical axis arranged behind the gun, and a member for closing an embrasure of the casemate, said member being shiftable on the gun barrel.

2. In a casemate gun the combination of a 70 plate connected with the gun and rotatable around a vertical axis arranged behind the gun, and a spherical member for closing an embrasure of the casemate, said member being shiftable on the gun barrel. 75

In testimony whereof, we have signed this specification in the presence of two subscribing witnesses.

KARL VÖLLER.
CARL WANINGER.
